DESIGN FOR A VENT PLUG FOR STORAGE BATTERIES

Robert M. Raney, Euclid, Ohio, assignor to Willard Storage Battery Company, Cleveland, Ohio, a corporation of West Virginia

Application January 5, 1937, Serial No. 66,896

Term of patent 14 years

To all whom it may concern:

Be it known that I, Robert M. Raney, a citizen of the United States, and a resident of Euclid, in the county of Cuyahoga and State of Ohio, have invented a new, original, and ornamental Design for a Vent Plug for Storage Batteries, of which the following is a specification, reference being had to the accompanying drawing forming a part thereof, in which

Fig. 1 is a plan view of a vent plug for storage batteries showing my new design;

Fig. 2 is a side elevation as viewed from the bottom of Fig. 1; and

Fig. 3 is a side elevation, the point of view being 90° from that of Fig. 2.

I claim:

The ornamental design for a vent plug for storage batteries substantially as shown.

ROBERT M. RANEY.
